(57) CLAIM

The ornamental design for a golf ball display cabinet, as shown and described.

DESCRIPTION

The claimed cabinet is used to display golf balls and could be hung on wall or placed on table/desk.

FIG. 1 is a perspective view of a golf ball display cabinet showing my new design, the undisclosed rear is unadorned; and,

FIG. 2 is a front elevational view thereof.

1 Claim, 2 Drawing Sheets

FIG. 1

FIG. 2
